UNITED STATES PATENT OFFICE.

CHARLES WALTER HACKETT, OF ATLANTA, GEORGIA, ASSIGNOR OF ONE-HALF TO
FRANK D. HACKETT, OF NORTHWILKESBORO, NORTH CAROLINA.

COMBINATION TIE-PLATE AND RAIL-BRACE.

1,312,905.

Specification of Letters Patent.

Patented Aug. 12, 1919.

Application filed March 21, 1916, Serial No. 85,690. Renewed July 5, 1919. Serial No. 308,913.

To all whom it may concern:

Be it known that I, CHARLES WALTER HACKETT, a citizen of the United States, residing at Atlanta, in the county of Fulton and State of Georgia, have invented certain new and useful Improvements in Combination Tie-Plates and Rail-Braces; and I do hereby declare the following to be a full, clear, and exact description of the invention, 10 such as will enable others skilled in the art to which it appertains to make and use the same.

The invention relates to improvements in tie plates.

15 The object of the present invention is to improve the construction of tie plates and to provide a combination tie plate and rail brace of simple, practical and comparatively inexpensive construction adapted to be cut 20 and formed from an ordinary tie plate at a very slight increase in the cost of the same and capable of serving as an ordinary tie plate in affording a firm bearing for the rail and prolonging the life of the cross tie by 25 preventing the rail from wearing into the tie and destroying or injuring the grain or fiber and thereby causing the tie to lose its grip or hold on the spikes and permitting the rails to spread.

30 A further object of the invention is to provide a tie plate equipped with means for bracing the rail at the outside thereof and effectually preventing the spreading of the rails and at the same time overcoming the 35 danger of a rail turning over due to the side thrust of a passing train resulting from cone-shape truck wheels, which side thrust is greatly increased on curves.

In the drawings

40 Figure 1 is a plan view of a combination tie plate and rail brace constructed in accordance with this invention, and shown applied to a rail,

Fig. 2 is a longitudinal sectional view of 45 the same,

Fig. 3 is an end elevation of the combination tie plate and rail brace,

Fig. 4 is a perspective view of a tie plate before the same is cut to form the rail brace,

50 Fig. 5 is a similar view, the tie plate being cut,

Fig. 6 is a perspective view of the tie plate after the same is cut and the partially severed portion bent upwardly at an inclination to form the brace,

Fig. 7 is a perspective view of the same after the partially severed portion has been shaped to form the brace.

Like numerals of reference designate corresponding parts in the several figures of the drawings.

In the accompanying drawings in which is illustrated the preferred embodiment of the invention, 1 designates an ordinary rolled tie plate which is cut by suitable dies 65 to form straight parallel longitudinal incisions 2 and a transversely disposed incision 3 connecting the longitudinal incisions and forming a central partially severed portion as clearly illustrated in Fig. 5 of the 70 drawings.

The partially severed portion is bent upwardly at an inclination as illustrated in Fig. 6 of the drawings and it is curved or rolled transversely to provide a longitudinally tapered brace 4 which presents a convex outer face and a concaved inner face which forms a longitudinal groove 5. The upper end of the brace 4 is beveled at 5^a to fit the underside of the head 6 of a rail 7 and the end edge 8 abuts against the web of 75 the rail. The lower end portion of the brace 4 and the adjacent portion of the base 1 are struck up and rounded, thus providing a strong durable connection between the brace 85 and base. The brace engages the rail at the angle formed by the outer portion of the head and the web and the bottom flange 9 of the rail fits in the crotch 10 formed by the lower end of the brace and the tie plate. 90 The rail is arranged upon the tie plate which is provided with spike receiving openings 11 located at opposite sides of the rail and also at the outer end of the plate 1. The spikes 12 engage the rail at the inner and 95 outer bottom flanges thereof and firmly maintain the base of the rail flat upon the tie plate. The tie plate is provided at its lower face with longitudinal ribs 13 and 14 for engaging a cross tie 15 to prevent the 100 tie plate from slipping thereon but the lower face of the tie plate may be constructed in any other desired manner as will be readily understood.

It will be seen that the combination tie 105 plate and rail brace is exceedingly simple and inexpensive in construction and that a maximum amount of strength particularly in the inclined brace is obtained from a minimum amount of metal owing to the 110

curving and tapering of the partially severed portions.

What is claimed is:—

- A combination tie plate and rail brace
5 comprising, a flat rectangular base having longitudinal and transversely extending incisions forming a centrally disposed partly severed portion adapted to be bent upwardly to function as a tie brace, said brace being
10 curved transversely to form a semiconical bracing member, the lower portion of the

bracing member and the adjacent portion of the base being struck up and rounded to form a strong durable connection between the base and brace.

15 In testimony whereof I affix my signature in presence of two witnesses.

CHARLES WALTER HACKETT.

Witnesses:

M. M. HOLLOWAY,
J. W. GRANADE.
